UNITED STATES PATENT OFFICE.

JAMES R. ELDRIDGE, OF YARMOUTH, NOVA SCOTIA, CANADA, ASSIGNOR TO HIMSELF AND REUBEN MCKINNON, OF SAME PLACE.

WHISTLE.

SPECIFICATION forming part of Letters Patent No. 407,067, dated July 16, 1889.

Application filed February 25, 1889. Serial No. 301,030. (No model.)

To all whom it may concern:

Be it known that I, JAMES R. ELDRIDGE, of Yarmouth, in the Province of Nova Scotia and Dominion of Canada, have invented a 5 new and useful Improvement in Whistles, of which the following is a full, clear, and exact description.

My invention relates especially to an improvement in steam-whistles, and has for its 10 object to provide a sound-deflector therefor, whereby the sound-waves will be deflected horizontally over a large area of surface; and a further object of the invention is to provide a deflector capable of the above function, of 15 simple construction, and which may be expeditiously attached to or detached from any form of whistle.

The invention consists in the combination, with steam-whistles, of a sound-deflector supported upon the same, and in the novel construction of the said deflector, as will be hereinafter more fully set forth, and pointed out in the claims.

Reference is to be had to the accompanying 25 drawings, forming a part of this specification, in which similar figures of reference indicate corresponding parts in all the views.

Figure 1 is a central vertical section through the deflector and a portion of the whistle, and 30 Fig. 2 is a plan view of Fig. 1.

In illustrating the application of my device I have shown one form of whistle comprising a steam-chamber 10, having a close top and two straight orifices 11 in the said top for the 35 escape of steam, said orifices being parallel, and a bell provided with two straight parallel side slots 13 to receive the steam as it issues from the orifices 11 and gives the sound; but I desire it to be distinctly understood that 40 any other form of whistle may be employed.

The sound-deflector 14 consists of a casting, either solid or hollow, the under surface whereof is curved. In constructing the sound-deflector a stem 15 is preferably projected 45 downward from the center of the under face, and the under surface is curved upward from the base of the said stem, as illustrated at 16 in Fig. 1, and as the said curve approaches the periphery of the deflector it is merged 50 into an essentially horizontal line, as illus-

trated at 17 in the same figure. The deflector is preferably circular in horizontal section, and the upper surface 18 is ordinarily convexed to dispose more readily of any water or snow falling thereon.

The deflector is provided with a vertical threaded bore extending through the stem and a threaded aperture in the top aligning the said bore in the stem.

In connecting the deflector with the whistle 60 a rod 19 is usually employed, one end of which rod is screwed or otherwise secured in the center of the upper surface of the steam-chamber 10. From thence the rod is projected vertically upward through the bell and beyond the same, the outer extremity of the rod being threaded. The deflector is secured upon the said rod and the stem is held essentially in contact with the upper surface of the bell by a lock-nut 20, screwed upon the 70 rod 19 to a contact with the upper surface of the deflector.

I desire it to be understood that I do not confine myself to the means illustrated for attaching the deflector to the whistle, or to 75 the general contour of the deflector, or to the form of the upper surface, as the said deflector may consist of a disk having a curved under surface.

Having thus described my invention, I claim 80 as new and desire to secure by Letters Patent—

1. The combination, with a steam-whistle, of a sound-deflector supported above the same, having a curved under surface, substantially as shown and described.

2. The combination, with a whistle, of a sound-deflector supported above the same, provided with a central stem upon the under surface, the exterior of which stem is caved, substantially as shown and described.

3. The combination, with a steam-whistle, of a sound-deflector supported above the same, provided with a central stem upon the under surface, and having the under face upwardly and outwardly curved from the base of the stem, which curve is merged into an essentially horizontal line near the periphery of the deflector, substantially as and for the purpose specified.

4. The combination, with a steam-whistle,

of a sound-deflector supported above the same, provided with a stem upon the under face, and having the under surface curved from the base of the stem essentially to the periphery of the deflector, and provided with a convex outer surface, and means, substantially as shown and described, for supporting

the said deflector, as and for the purpose specified.

JAMES R. ELDRIDGE.
